CLAIM

The ornamental design for a display screen or portion thereof with graphical user interface, as shown and described.

DESCRIPTION

FIG. 1 is a front view of the first embodiment of a display screen or portion thereof with graphical user interface showing my new design;

FIG. 2 is a front view of a second embodiment thereof; and, FIG. 3 is a front view of a third embodiment thereof.

The broken lines in the figures show portions of the graphical user interface that form no part of the claimed design.

1 Claim, 3 Drawing Sheets
